UNITED STATES PATENT OFFICE.

JACOB R. RYDER, OF ASHLAND, OHIO, ASSIGNOR TO THE ASHLAND PRODUCTS COMPANY, OF ASHLAND, OHIO, A CORPORATION OF OHIO.

LIFTING JACK.

Application filed August 18, 1922. Serial No. 582,760.

To all whom it may concern:

Be it known that I, JACOB R. RYDER, a citizen of the United States, residing at Ashland, in the county of Ashland and 5 State of Ohio, have invented certain new and useful Improvements in Lifting Jacks, of which the following is a specification.

This invention relates to lifting jacks, and more particularly to jacks provided 10 with a pair of pawls having control means therefor, whereby the device may be employed for lowering the work as well as raising it.

An important object of the device is to 15 provide simple accessible control means as above outlined for controlling the action of the pair of pawls for lowering the standard or raising it to lift the work.

Other objects and advantages of the invention will become apparent during the 20 course of the following description.

In the drawings, I have shown one embodiment of the invention. In this showing:

25 Figure 1 is a side elevation,

Figure 2 is a central vertical longitudinal sectional view,

Figure 3 is a plan view,

Figure 4 is an end elevation,

30 Figure 5 is a fragmentary sectional view similar to Figure 2 somewhat enlarged.

Figure 6 is a section on line 6—6 of Figure 5,

35 Figure 7 is a detailed perspective of the holding pawl and its associate spring, and,

Figure 8 is a similar view of the pawl control member.

In the drawings, the numeral 10 designates a standard preferably formed of 40 stamped sheet steel, the standard being formed substantially U-shaped in cross section as shown in Figure 6 to provide side walls 11 and an end wall 12, the opposite end being open as shown. A brace 11' is 45 mounted between the upper ends of the side walls 11. The standard is mounted upon a base 13 and is secured thereto by angle braces 14 through rivets 15.

A lift bar 16 is slidably mounted in the 50 standard against the end wall 12 thereof, as clearly shown in Figure 6, the lift bar preferably contacting the side walls 11 of the standard to prevent side sway. The lift

bar 16 is provided upon its inner face with a longitudinal set of ratchet teeth 17 having substantially horizontal lower faces. A guide member 18 is connected between the side walls 11 of the standard to prevent the lower end of the lift bar from swinging inwardly, while the lower end of the latter 60 is provided with a stop pin 19 adapted to engage the guide 18 to limit the upward movement of the lift bar.

The numeral 20 designates an operating lever as a whole, comprising a handle 21 and a handle socket 22. The socket 22 is formed of a pair of complementary stamped members 23 and 24 provided through a portion of their length with flanges 25 which are secured together by rivets 26. The inner 70 ends of the members 23 and 24 are spaced to form arms 27 and 28. A pivot pin 29 extends through the arms 27 and 28 and is mounted in the side walls 11 of the standard to provide pivot means for the operating lever. A pin 30 is connected between the side walls 11 of the standard and is adapted to be received in a recess 31 in the operating lever to limit the downward movement of the outer end thereof.

Between the spaced arms 27 and 28 is mounted a holding pawl 32 which is also pivoted upon the pin 29 so that oscillating movement of the operating lever does not affect its movement. As shown in Figure 85 2, the upper end of the pawl 32 is adapted to engage the teeth 17. A spring 33 is coiled about the pin 29, the upper end of the spring being adapted to contact with the pawl 32 adjacent the upper end thereof, a 90 lip 34' being formed upon the pawl 32 to prevent transverse displacement of the spring. The lower end of the spring 33 is adapted to bear against a pin 34 which is mounted between the inner ends of the arms 27 and 28 but is not connected with the side walls 11 of the standard, as will be understood. It will be apparent that the tension of the spring 33 tends to move the upper end of the pawl 32 inwardly into engagement with the teeth 17. The lower end of the pawl 32 projects downwardly below the pin 29 as at 35, for a purpose to be described.

An operating pawl 36 is pivoted upon 105 the pin 34 and has its upper end adapted

to engage the teeth 17, as shown in Figures 2 and 5. A spring 37 is coiled about the pin 34, the lower end of the spring being adapted to bear against the pin 29 while the 5 upper end thereof engages the pawl 36 adjacent the upper end thereof whereby the latter is normally projected into engagement with the teeth 17. A lip 38 is formed upon the pawl 36 adjacent its upper end to prevent 10 transverse displacement of the spring 37. The pawl 36 extends a substantial distance downwardly below the pin 34 and is provided at its lower end with an inclined face 39 for a purpose to be described.

15 The numeral 40 designates a pawl control member preferably comprising a piece of sheet metal having a flat longitudinal portion 41 pivoted as at 42 upon the pin 29. A pair of spaced arms 43 and 44 are formed 20 upon the longitudinal portion 41 and extend inwardly transversely thereof. As shown in Figures 2 and 5, the projecting end 35 of the pawl 32 is mounted between the arms 43 and 44. The inclined face 39 25 of the pawl 36 is arranged adjacent the arm 44 of the control member.

The numeral 45 designates as a whole, a control spring which is preferably formed 30 of a leaf spring bent upon itself intermediate its ends to form upwardly diverging ends 46 and 47. The spring 45 is mounted upon a transverse pin 48 connected between the side walls 11 of the standard. As shown in Figure 5, the inner arm 46 of the spring 45 35 has its upper end arranged between the arms 43 and 44 and in contact with the latter. The numeral 49 designates a spring control member which is substantially U-shaped, as shown in Figure 4. The member 49 is 40 pivoted upon a transverse pin 50 connected between the side walls 11 of the standard and is provided with a lip 51 whereby it may be swung to selected positions. As shown in Figure 5, the inner portion of the 45 U-shaped member 49 is adapted to engage the shorter arm 47 of the spring 45. In the position shown in Figure 2, with the outer end of the member 49 swung upwardly, tension upon the arm 46 of the spring 45 is released, while in the position 50 shown in Figure 5, tension is placed upon the portion 46 of the spring to normally project the arms 43 and 44 of the control member inwardly.

55 The operation of the device is as follows: When it is desired to lift the work, such as an automobile axle, the member 49 is swung to the position shown in Figure 2, relieving tension upon the arm 46 of the 60 spring 45. In this position, the springs 33 and 37 are free to project the upper ends of the pawls into engagement with the teeth 17. Downward movement of the outer end of the operating lever lifts the pawl 36 65 which in turn raises the lift bar 16. Dur-

ing the lifting operation of the lift bar, it will be apparent that the pawl 32 trips over the teeth 17 until the outer end of the operating lever reaches its lowermost position. The pawl 32 then supports the lift 70 bar 16 while the outer end of the operating lever is being moved upwardly, the pawl 36 tripping downwardly over the teeth 17 until the outer end of the operating lever reaches its uppermost position. This action 75 is repeated until the work is raised the desired height, as will be understood.

When it is desired to lower the work, the member 49 is swung downwardly to the position shown in Figure 5 whereupon a 80 tension will be exerted upon the arm 46 of the spring 45 to project the arms 43 and 44 of the control member 40 inwardly. In this position of the above members, the arm 43 tends to move the extension 35 inwardly 85 and disengage the upper end of the pawl 32 from the teeth 17. Outward movement of the upper end of the pawl 32 is prevented when the handle is in the uppermost position, but is permitted when the latter is in 90 the lowermost position, as shown in Figure 5. In this position, the pawl 32 is disengaged from the teeth while the load is placed upon the pawl 36. Upward movement of the handle lowers the pawl 36, the lift bar 16 being permitted to move downwardly until the handle reaches its lowermost position. When the handle reaches a point slightly spaced from the upper limit 100 of its stroke, the inclined face 39 engages the arm 44 moving the lower end of the member 40 outwardly, whereby the projection 35 is relieved of the tension of the spring arm 46. The spring 33 then projects the upper end of the pawl 32 into engagement with one of the teeth 17. The handle is then moved downwardly, the load being shifted from the pawl 36 to the pawl 32, whereupon the arm 44 under tension of the spring arm 46 moves the upper end of 105 the pawl 36 out of engagement with the teeth 17. During the complete downward movement of the handle, the lift bar 16 is held stationary by the holding pawl 32. As the handle approaches the lower limit 110 of its stroke, the inclined face 39 is released from the arm 44, whereupon the spring 37 moves the upper end of the pawl 36 into engagement with one of the teeth 17. When 115 the handle starts upon its upward stroke, the load is then shifted from the pawl 32 to the pawl 36 and the spring arm 46 acting upon the projection 35, releases the upper end of the pawl 32 from engagement with the ratchet teeth.

120 It is to be understood that the form of my invention herewith shown and described is to be taken as a preferred example of the same, and that various changes in the shape, size, and arrangement of parts may be 125

resorted to without departing from the spirit of the invention or the scope of the subjoined claims.

Having thus described my invention, I

5 claim:

1. A lifting jack comprising a standard, a lift bar slidably connected therewith and provided with ratchet teeth, an operating lever pivotally connected with said standard, a holding pawl pivotally connected with said standard, an operating pawl pivotally connected with said operating lever, the upper end of each of said pawls being adapted to engage said ratchet teeth, yielding means to normally move said pawls into engagement with said teeth, a control member including a pair of transverse arms adapted to alternately engage the lower ends of said pawls to move them out of engagement with said ratchet teeth, and resilient means engaging one of said arms for rendering said control member effective.

2. A lifting jack comprising a standard, a lift bar slidably connected therewith and provided with ratchet teeth, an operating lever pivotally connected with said standard, a holding pawl pivotally connected with said standard, an operating pawl pivotally connected with said operating lever, the upper end of each of said pawls being adapted to engage said ratchet teeth, yielding means to normally move said pawls into engagement with said teeth, a control member including a pair of transverse arms adapted to alternately engage the lower ends of said pawls to move them out of engagement with said ratchet teeth, a leaf spring

contacting with one of the arms of said control member to actuate it, and means for selectively rendering said spring effective 40 and ineffective.

3. A lifting jack comprising a standard formed substantially U-shaped in cross section to provide side walls and an end wall, a lift bar slidably mounted between the side walls of and in contact with the end wall of said standard, said bar being provided with ratchet teeth, a pivot pin mounted between the side walls of said standard, an operating lever mounted upon said pivot pin and projecting from the open side of said standard, a holding pawl pivotally mounted on said pin, an operating pawl pivotally connected with said operating lever, the upper end of each of said pawls being adapted to engage said ratchet teeth, yielding means to normally move said pawls into engagement with said teeth, a control member pivotally mounted on said pivot pin and depending therefrom adjacent one of the side walls of said standard and having a pair of transversely extending arms adjacent its lower end adapted to alternately engage the lower ends of said pawls to move them out of engagement with said ratchet teeth, and resilient means engaging said control member for rendering it effective.

In testimony whereof I affix my signature in presence of two witnesses.

JACOB R. RYDER.
